UNITED STATES PATENT OFFICE.

HARVE REED STUART, OF SPRINGFIELD, OHIO, AND FREDERIC SCHAEFER, OF PITTSBURGH, PENNSYLVANIA.

ELECTRIC BELL.

1,048,913.

Specification of Letters Patent.

Patented Dec. 31, 1912.

Application filed February 20, 1912. Serial No. 678,796.

To all whom it may concern:

Be it known that we, HARVE REED STUART, a resident of Springfield, in the county of Clark and State of Ohio, and FREDERIC SCHAEFER, a resident of Pittsburgh, in the county of Allegheny, State of Pennsylvania, have invented a new and useful Improvement in Electric Bells, of which the following is a specification.

10 This invention relates to electrically actuated signaling devices, such as bells.

The main object of the invention is to provide an electrically actuated signaling device which can be connected to ordinary 15 commercial alternating circuits without the intervention of a transformer and whereby dangerous grounds or short circuits are guarded against.

Further objects are to provide mechanism 20 of strong, reliable, and yet cheap construction.

The invention comprises the circuit connections and arrangement of parts herein-after described and claimed.

25 In the accompanying drawings Figure 1 shows partly in plan view and partly diagrammatically an electric bell embodying the invention; Fig. 2 is a diagram showing a modification; and Fig. 3 is a detail view 30 of the armature and ball tapper.

The signaling device has been illustrated as an ordinary bell or gong 1 of usual construction adapted to be sounded by a vibrating hammer or clapper 2, carried by an 35 oscillatory armature 3 pivotally mounted at 4 intermediate its ends. Adjacent to the opposite ends of the armature are a pair of poles 5 and 6, one opposite each end of the armature. These are formed as extensions

40 from one arm or pole of a strong permanent magnet 7 of horseshoe form, the armature being pivotally mounted adjacent to the opposite pole of said armature. The consequence is that the two poles 5 and 6 are of

45 the same polarity when no current is circulating through the windings, while the armature 3 is of the opposite polarity.

Surrounding each of the extensions 5 and 6 is a magnet coil, the two coils being 50 marked 8 and 9, respectively, and are arranged to be connected respectively in opposite sides of the line. As shown, one side

of the line 10 is connected to binding post 11. To the same post is connected one end 12 of coil 8, the opposite end 13 of said coil 55 being connected to binding post 14. The other side 15 of the line is connected to binding post 16. To the same binding post is connected one end 17 of coil 9, the other end 18 of said coil being connected to binding post 19. To the binding posts 14 and 19 are connected circuit wires 20 and 21, respectively, in which are connected one or more circuit closers or push buttons 22 for the purpose of closing the circuit to actuate 60 the bell.

It will be observed that the two coils 8 and 9 are connected respectively in opposite sides of the circuit, and that the circuit closer or push button is in series with both 70 coils and between the same. The coils 8 and 9 are composed of turns of very fine wire, having high ohmic resistance, and very material self-inductance, so that they choke or cut down the current, to allow only a very 75 small amperage to flow through the coils. The consequence is that as soon as the circuit is closed at the push button or circuit closer 22 the voltage drops abruptly at the button, thereby rendering an ordinary push 80 button perfectly safe and not liable to deterioration from sparking when the circuit is again broken. Since the push button is between the coils, a safeguard is provided against dangerous grounds or short circuits 85 between the button wires 20 and 21 and one side of the line which would exist if the circuit closer were in series with the two coils and between one thereof and one side of the line. When no current circulates in the 90 coils both cores are of the same polarity, say "N" poles, while the armature presents "S" poles, these poles being induced by the permanent magnet. Upon closing the circuit at 22 the alternating current flows 95 through the two coils 8 and 9 in series. When one-half of the wave is flowing, the "N" pole of one coil is strengthened or built up, while the pole of the other coil is weakened and may even be reversed so as to 100 become an "S" pole. The armature, however, remains of the same polarity as before. Its one end is, therefore, attracted strongly by the strong "N" pole, while its opposite

end is scarcely attracted at all by the weak "N" pole or it may even be repelled should this pole be of "S" polarity. When the following half of the wave flows through the coils, the conditions in the coils are reversed and the armature is attracted in the opposite direction. The consequence is that with an alternating current the poles 5 and 6 are alternately strengthened and weakened to produce oscillation of the armature 3.

When one end of the armature is in contact with the corresponding pole, say the pole 5, there is a considerable air gap between the opposite end of the armature and the pole 6, which must be overcome before attraction between the contacting pole 5 and armature can be broken. The consequence is that the pole 6 must be materially strengthened before the pole 5 releases the armature, and when the latter is overcome the relatively great strength of the opposite pole brings the armature in contact therewith with a snap, which produces energetic actuation of the armature and energetic operation of the bell. If the armature would vibrate upon very small differences in strength of the two poles 5 and 6 only feeble actuation of the bell could result, but by having the two poles 5 and 6 of the same polarity and relatively strong magnetism, it requires a much greater variation in the strength of the two poles to produce oscillation of the armature, but the oscillations will be much more energetic, as just pointed out. The consequence is that the device gives a strong signal.

Fig. 2 shows a modification in which one of the coils is split, one part 8^a surrounding one core 5 and the other part 8^b surrounding the other core 6, along with the other coil 9^b. The effect here is the same in principle as in the preferred form.

By having relatively weak coils the device is rendered comparatively inexpensive, as the spools or coils constitute a considerable item of expense, particularly where these coils must be large and strong.

The bell described can be connected directly in any commercial alternating circuit, the most common of which are of 110 volts. It operates perfectly upon an alternating circuit of this voltage, without the use of a transformer and without dangerous grounds or short circuits. On account of the high resistance and self-inductance of the coils the current is cut down and the voltage also drops suddenly at the circuit closer as soon as the latter is closed, and the location of the circuit closer between the two sections of coil prevents dangerous grounds and short circuits, as hereinbefore pointed out, and this makes it safe to use the bell upon relatively high voltage circuit without the use of a transformer.

The signal device can be of any character adapted to be actuated by the oscillating armature. It need not necessarily be a bell or gong. For the purpose of strength, the armature 3 and hammer or clapper 2, and preferably also the pivots 4, are made of a single piece so as to withstand severe vibration. This is shown in Fig. 3.

A short circuit between opposite sides of the circuits to the coils 8 and 9 has no other effect than to ring the bell. For instance a short circuit between wire 12 or wire 13 and wire 18 or binding post 19, or between wire 17 or wire 18 and wire 13 or binding post 14 produces the same effect as if the circuit closer 22 were closed. The circuit arrangement shown with a coil on each side of the push button or circuit closer is therefore especially advantageous, as it entirely obviates evil effects in case of short circuits.

What we claim is:

1. In an alternating current signal, the combination of a winding in two parts, the two parts arranged to be connected, one in one side of the line and the other in the other side of the line, a current closer arranged to be connected between the two parts of the winding and in series therewith, an armature arranged to be actuated by said winding, and a signal device actuated from said armature.

2. In an alternating current signal, the combination of a winding in two parts, the two parts arranged to be connected, one in one side of the line and the other in the other side of the line, permanently magnetized cores for said windings, a circuit closer arranged to be connected between the two parts of the winding and in series therewith, an armature arranged to be actuated by said winding, and a signal device actuated from said armature.

3. In an alternating current signal, the combination of a winding in two parts, the two parts arranged to be connected, one in one side of the line and the other in the other side of the line, permanently magnetized cores of the same polarity for said windings, a circuit closer arranged to be connected between the two parts of the winding and in series therewith, an oscillatory armature arranged to be actuated by said winding and a signal device actuated from said armature.

4. In an alternating current electric signal, the combination of a pair of coils, one connected in one side of the line and the other in the other side of the line, permanently magnetized poles for said coils, an oscillating armature adjacent to said poles arranged to be oscillated by the alternate attraction of said poles, a circuit closer in series with the coils and between the same, and a signal device arranged to be actuated by the oscillation of said armature.

5. In an alternating current electric signal, the combination of a permanent magnet, a pair of extensions from one pole thereof, a coil on each extension, one coil arranged
5 to be connected to one side of the line and the other to the other side of the line, an oscillating armature arranged with an end adjacent to a pole of each of said coils, a circuit closer arranged to be connected in
10 series with said coils and between the same, and a signal device arranged to be actuated by the oscillation of said armature.

In testimony whereof, we have hereunto set our hands.
